UNITED STATES PATENT OFFICE.

HARRY O. RUGH, OF SANDWICH, ILLINOIS.

SIGNALING-CIRCUIT.

No. 897,413.

Specification of Letters Patent.

Patented Sept. 1, 1908.

Application filed May 2, 1908. Serial No. 430,458.

To all whom it may concern:

Be it known that I, HARRY O. RUGH, a citizen of the United States, residing at Sandwich, in the county of Cook and State of Illinois, have invented a certain new and useful Improvement in Signaling-Circuits, of which the following is a full, clear, concise, and exact description, reference being had to the accompanying drawings, forming a part of this specification.

My invention relates to signaling circuits and apparatus, and will be well understood by reference to the accompanying drawing, showing the preferred embodiment thereof, there being illustrated in the drawing a signal-receiving station and a signal-sending station, together with suitable apparatus for receiving and sending signaling current.

The invention is of particular utility in connection with telephone exchange systems, though it is not to be restricted to this service.

I have shown a signal-receiving bell *a* included in circuit with a transmission line whose limbs *b b* terminate in springs *c c* of a spring-jack. A connecting plug is provided with contact terminals that are adapted to engage the spring *c c* so that the cord circuit *d* may be caused to constitute a continuation of the transmission line *b*. I have illustrated the springs *e* of a ringing key in connection with the strands of the cord circuit *d*, the normal contacts of these springs effecting continuation of the cord circuit, as is well understood, while the alternate contacts of these springs constitute terminals connected with the circuit of a pole-changing apparatus to be described. The position of the springs *e* is determined by the operator at the station where the cord circuit equipment and the pole-changing apparatus is located.

The improved apparatus which I employ for changing the polarity of the current impressed upon the alternate contacts of the ringing key *e* will now be described. The ringing battery or other suitable source of direct current is indicated at *f*, the poles of this battery being permanently connected with contact elements or springs *g h*. These springs *g* and *h* are provided with normal contacts and with alternate contacts. When the springs *g* and *h* are in engagement with the normal contacts, current is impressed upon the alternate contacts of the ringing key *e* in a direction which may, for example,

be represented by the arrows shown in full lines. When the springs *g* and *h* are in engagement with their alternate contacts, current is impressed upon the alternate contacts of the ringing key in the reverse direction, represented by the dotted arrows. A polarized relay *i* is included in circuit with battery *f* and desirably in series therewith, this polarized relay being located between the contacts of the battery terminals *g* and *h* and the alternate contacts of the ringing key *e*, so that irrespective of the direction of the current flowing to the alternate contacts of the ringing key, the polarized relay *i* always receives current when such current is passing to the ringing key.

The polarized relay *i* has armature contacts which govern a local circuit including an electro-magnet *k* and a battery *l*, this magnet *k* being employed for the purpose of moving the contact terminals or springs *g* and *h* from engagement with their normal contacts to engagement with their alternate contacts, the magnet *k* acting against the force of a spring *m*, which serves to bring the elements *g* and *h* into engagement with their normal contacts when the magnet *k* is not in service. It is understood, of course, that the magnet *k* possesses a force which is in excess of the spring *m*, whereby the shift of the battery terminals *g* and *h* may be effected from their normal contacts to their alternate contacts. When the operator closes the ringing key, the current that is then passed to the alternate contacts of the ringing key and through the relay *i* has a direction represented by the arrows in full lines, which direction is such as to shift the armature of the relay *i* to the left, thereby to close the circuit of the magnet *k*, so as to attract the battery terminals *g h* against the force of the spring *m*. When the battery terminals *g* and *h* are engaged with their alternate contacts as a consequence of the operation of the electro-magnet *k*, current through the polarized relay *i* is reversed, as indicated by the arrows in dotted lines, whereby the armature of the relay *i* is moved to the right to open the local circuit including the magnet *k*, whereupon the spring *m* is permitted to restore the battery terminals *g h* to their normal position.

It sometimes happens that the ringing key is released at a time which will not permit the sufficient flow of current in the direction indicated by the dotted arrows, to enable the relay *i* to open the circuit of the magnet *k*.

To prevent such an occurrence, I provide means, supplementing the ringing key, whereby current through the relay *i* in the direction of the dotted arrows may be continued, so that the armature of said relay *i* is moved to the right, thereby to open the circuit of the magnet *k* and permitting the spring *m* to restore the terminals *g* and *h* to their normal positions. The supplementing means desirably resides in a conductor *n* containing a high resistance *o* of, say, eleven thousand ohms, which serves to continue the current from the battery *f* through the polarized relay *i* in the direction indicated by the dotted arrows, because of the establishment of a circuit which includes the battery *f*, the conductor *n*, the resistance *o*, the polarized relay *i*, the alternate contact of battery terminal *h*, and said battery terminal, this circuit occasioning the restoration of the armature of the polarized relay to its normal right-hand position, thereby opening the circuit of the magnet *k* and permitting the spring *m* to restore the battery terminals *g* and *h* to normal.

While I have herein shown and particularly described the preferred embodiment of my invention, I do not wish to be limited to the precise construction and arrangement shown, as modifications may readily be made therein without departing from the spirit of the invention, but

Having thus described my invention, I claim as new and desire to secure by Letters 35 Patent:—

1. A pole-changing device including a source of current, switch elements constituting terminals of said source of current, a normal contact for each of said switch elements, an alternate contact for each of said switch elements, a conductor connected with one normal and one alternate contact, a second conductor connected with the other normal and the other alternate contact, a polarized relay connected in circuit with said conductors, a magnet for effecting engagement between said switch elements and their alternate contacts, the switch arm of the polarized relay including said electro-magnet in circuit when said relay is included in circuit with the normal contacts of said switch elements, and serving to remove said electro-magnet from circuit when said relay is included in circuit with the alternate contacts of said switch elements, in combination with a switch or key for connecting the said conductors in circuit with a suitable translating device responsive to the currents of changed directions, said key also controlling the circuit relationship of said polarized relay, and a conductor including high resistance, included in circuit with said source of current, one of its switch terminals, the alternate contact of said terminal and the polarized relay, where- 65 by the operation of said polarized relay to

remove said electro-magnet from circuit is insured.

2. A pole-changing device including a source of current, switch elements constituting terminals of said source of current, a normal contact for each of said switch elements, an alternate contact for each of said switch elements, a conductor connected with one normal and one alternate contact, a second conductor connected with the other normal and the other alternate contact, a polarized relay connected in circuit with said conductors, a magnet for effecting engagement between said switch elements and their alternate contacts, the polarized relay including said electro-magnet in circuit when said relay is included in circuit with the normal contacts of said switch elements, and serving to remove said electro-magnet from circuit when said relay is included in circuit with the alternate contacts of said switch elements, in combination with a switch or key for connecting the said conductors in circuit with a suitable translating device responsive to the currents of changed directions, said key also controlling the circuit relationship of said polarized relay, and means supplementing the said key for maintaining the polarized relay in circuit with the alternate contacts in the event of the failure of said key so to do, whereby the removal of said electro-magnet from circuit is insured.

3. A pole-changing device including a source of current, switching mechanism for reversing said current, an electro-magnet for moving the switching mechanism, a polarized relay receiving the current of different directions, operating, when receiving the current of one direction, for including said electro-magnet in circuit to effect its energization, and, when receiving current of another direction, to remove said electro-magnet from circuit, in combination with a switch or key for enabling the impression of currents of changed directions upon a suitable translating device, said key also controlling the circuit relationship of said polarized relay, and a conductor including high resistance, included in circuit with said source of current and said polarized relay when the first aforesaid switching mechanism is moved by its operating electro-magnet, whereby the operation of said polarized relay to remove said electro-magnet from circuit is insured.

4. A pole-changing device including a source of current, switching mechanism for reversing said current, an electro-magnet for moving the switching mechanism, a polarized relay receiving the current of different directions, operating, when receiving the current of one direction, for including said electro-magnet in circuit to effect its energization, and, when receiving current of another direction, to remove said electro-magnet from circuit, in combination with a

switch or key for enabling the impression of currents of changed directions upon a suitable translating device, said key also controlling the circuit relationship of said polarized relay, and means supplementing the said key for maintaining the polarized relay in a given circuit condition, whereby the removal of said electro-magnet from circuit is insured.

5. A pole-changing device including a source of current, switch elements constituting terminals of said source of current, a normal contact for each of said switch elements, an alternate contact for each of said switch elements, a conductor connected with one normal and one alternate contact, a second conductor connected with the other normal and the other alternate contact, a polarized relay connected in circuit with said conductors, and a magnet for effecting engagement between said switch elements and their alternate contacts, the polarized relay including said electro-magnet in circuit when said relay is included in circuit with the nor-

mal contacts of said switch elements, and serving to remove said electro-magnet from circuit when said relay is included in circuit with the alternate contacts of said switch elements.

6. A pole-changing device including a source of current, switching mechanism for reversing said current, an electro-magnet for moving the switching mechanism, and a polarized relay receiving the current of different directions, operating, when receiving the current of one direction, for including said electro-magnet in circuit to effect its energization, and, when receiving current of another direction, to remove said electro-magnet from circuit.

In witness whereof, I hereunto subscribe my name this 30th day of April A. D., 1908.
